CLAIM

The ornamental design for a thermostat, as shown and described.

DESCRIPTION

FIG. 1 illustrates a perspective view of a thermostat;
 FIG. 2 illustrates a top view of the thermostat of FIG. 1;
 FIG. 3 illustrates a bottom view of the thermostat of FIG. 1;
 FIG. 4 illustrates a front view of the thermostat of FIG. 1;
 FIG. 5 illustrates a back view of the thermostat of FIG. 1;
 FIG. 6 illustrates a left side view of a thermostat of FIG. 1;
 and,

FIG. 7 illustrates a right side view of a thermostat of FIG. 1.
 The broken lines are included for the purpose of illustrating
 portions of the Thermostat and form no part of the claimed
 design.

1 Claim, 5 Drawing Sheets(56)
